UNITED STATES PATENT OFFICE

2,455,884

INFANT'S SLEEPING GARMENT
COMBINATION

Libera L. Steigerwald, Chicago, Ill.

Application April 19, 1944, Serial No. 531,737

2 Claims. (Cl. 128—134)

1

This invention relates to an infant's sleeping garment combination, and more particularly to a garment device for keeping a child in proper position in bed and properly beneath the covers while preventing the child from injuring itself. Efforts have heretofore been made to construct devices for restraining a baby or small child in bed so that the child will remain covered and protected against cold and exposure. However, in such devices, it has not been possible to provide freedom of movement for the child beneath the covers while at the same time securely holding the child beneath the covers. This is particularly true as to the turning over of the child in bed beneath the covers. It is particularly important in a device of this type that a child be able to turn over readily without danger of entanglement in the covers and at the same time without permitting the child to escape from beneath the covers. In addition, prior devices in many instances have permitted the child to become entangled in straps, harness, etc., and in some cases children have been seriously injured because of such entanglement.

It is an object of the present invention to provide a combination device which will satisfy the requirements as above outlined and which will be effective in holding the child in the proper position during sleeping periods. Another object is to provide a sleeping garment combination which will leave the child with the greatest possible freedom of movement while at the same time keep him from getting clear of the bed covers. A specific object is to provide a combination device in which a body garment unit is secured to the bed covers through a tie member which extends from the crotch of the body unit, so that as the child turns the tie member will twist but will not entangle the child's legs or arms.

Further objects and advantages of the invention will be apparent as the specification proceeds.

Preferred embodiments of the invention are illustrated in the accompanying drawings, in which—

Fig. 1 is a perspective view of the under side of the improved device; Fig. 2, a perspective view the same as Fig. 1 except with the device opened and the body unit and tie member turned back; Fig. 3, a perspective view of the body unit and tie member showing the back side of this body unit; Fig. 4, an enlarged sectional view as seen from the line 4—4 of Fig. 1; and Fig. 5, a perspective view of a modified form of the body unit and tie member.

The improved device includes a bed cover 10

which, as illustrated, is formed of a top sheet 11, side flaps 12 and 13, and the lower end flap 14. The top sheet 11 is joined with the flap 12 along the longitudinal seam 15 and is joined with the flap 13 along the longitudinal seam 16. The end flap 14 is attached to the sheet 11 by the seam 17. Suitably, the sheet 11 and flaps 12, 13 and 14 may all be formed from a single sheet of fabric material.

The sheet 11 is provided with the longitudinal plaits 18 and 19 which are preferably located just adjacent the edges of this sheet and adjoining the seams 15 and 16. These plaits serve to provide extra fullness under the cover to allow for additional freedom of movement. When not in use, the cover will lie flat, and the sheet 11 will present a rectangular outline of neat appearance, but when the cover is placed over a child in the use of the device, the plaits 18 and 19 will expand, permitting the sheet 11 to bulge upwardly, allowing ample room for movement of the child's arms, legs, etc. Though the structure in which the plaits 18 and 19 are located as they are preferred, plaiting means of fullnesses of any desired form may be used, and such may be located along the surface of the sheet 11 at any suitable point.

The top edge of the sheet 11 may be provided with the hem 20, and extending from the base of this hem at one side are the tie straps 21 and extending from the other side of the sheet at the base of the hem 20 are the tie straps 22. The tie straps 23 and 24 extend from the bottom corners of the sheet, and each of these tie straps may be secured to the corners of the bed or pen structure.

Another set of tie straps 25 is attached to the cover at the bottom center of the sheet 11. This set of tie straps may be secured to a bed frame and will serve to receive the strain occasioned by any pull on the center of the sheet due to the tie member 40, later to be described.

As indicated at Fig. 2 of the drawings, the sheet 10 has on its under side a strip 23 which is sewed to the sheet 11 at a point about the middle between the two sides and spaced from the bottom of the sheet. To this strip are secured the loops 24 which are adapted to receive buttons. Preferably, another series of loops 25 is secured in like manner at a different spacing from the bottom of the sheet, and in the embodiment illustrated there is a third series of loops 26 secured at the bottom edge of the sheet. Any number of such loop attachments may be employed as desired, and the spacings may be varied. If de-

sired, any other suitable fastening means may be substituted for the button and loop arrangement contained in the embodiments illustrated.

Referring more particularly to Figs. 2 and 3 of the drawings, the body unit 27 may comprise a front portion 28 which is adapted to extend over the child's chest and abdomen and the back portion 29 which is adapted to extend over the child's back. The armholes 30 and 31 are provided through which the child's arms may protrude, and the back is split longitudinally at 32, tied by the bows 33. Any suitable means for opening the garment and for releasably closing the opening may be employed.

As shown in Fig. 3, the back portion 29 extends downwardly over the child's buttocks and at its end portion is provided with buttonholes 34. The front portion 28 extends downwardly over the child's abdomen and is provided with the buttons 35 which may engage the buttonholes 34 to secure the front and rear members in a crotch portion. This structure provides the openings 36 and 37 through which the infant's feet may extend. Sleeve and leg members may be utilized with the body unit, if desired.

The body unit is intended to fit snugly about the child's body and is intended to move as the child moves. Preferably, this body unit is unrestricted and not attached to the bed or bed clothes, except for the attachment of the tie member to the crotch portion. It will be noted that the infant can in no way escape from the garment when it is closed around his body, and it is not possible for the child to release his arms or legs from the openings in this body unit as it would be possible for him to do in the case of the jacket or nightgown type of garment.

The piece forming the front portion 28 may extend downwardly beyond the buttons 35 to form the tie member 40. This tie member may be of any desired form or contour. At its lower end, it may be provided with fastening means, such as the buttons 38, which are adapted to engage the loops 24, 25 or 26 on the under side of the sheet 11.

Though it is preferable that the tie member 40 be formed by an integral extension of the front body portion 28, as is illustrated in Fig. 3, it is also satisfactory and efficient to have the tie member 40 formed as an integral extension of the rear body portion 29, and in this case the front body portion would be releasably attached by suitable means to the rear portion 29 to form the crotch.

The tie member 40 need not necessarily be an extension of the same piece which forms the front or back of the body structure, but if desired may be a separate and distinct piece which is attached to the body unit in any suitable way and extends from the crotch portion. The ends of such a piece may be attached to the body unit at any point thereon, but the piece should extend from and be secured to the crotch portion of the body garment.

Preferably, the tie member 40 is of such length that when attached to one of the loops 24, 25 or 26, and the cover 10 drawn up in the position shown in Fig. 1, the child's head will extend beyond the top edge of the cover sheet 11. The loops at different spacings along the sheet 10 provide for different sized body portions and tie members so that different sized children can be accommodated and so that the cover will accommodate the growth of a baby or child. Also, by having the loops 24, 25 and 26 at different lon-

gitudinal spacings, the attendant may place the child so that only the head is beyond the cover sheet or so that the head and chest also are beyond the cover, as may be desired, simply by selecting the appropriate position (24, 25 or 26) at which to attach the tie member 40.

The cover structure 10, and also the body unit 27 and tie member 40, may be formed of any suitable material, such as muslin or other cloth. Suitably, the cover 10 may be of flannel material while the infant's body unit 27 and tie member 40 may be of muslin, or any desired flexible sheet material may be employed.

In the use of the improved garment structure shown in Figs. 1 to 4, the cover 10 is laid open as indicated in Fig. 2 of the drawing, and the child is placed in the body unit. By untying the bows 33, the baby or child may be lowered into the garment unit and his feet will protrude through the openings 36 and 37, the arms will protrude through the armholes 30 and 31, and the garment unit may be closed by fastening the ties 33. The child after being placed in the garment may be laid on his back or on his stomach in the bed, and the cover 10 may be drawn over the child, with the hem 20 coming to a position adjacent his neck. Because the buttons 38 may be readily attached to the loops 24, with either side of the garment turned upwardly, it is possible to lay the child in the garment on the bed either on its stomach or on its back. The side flaps 12 and 13 and the end flap 14 may be tucked in about the sides, and the corners of the cover may be fastened to the corners of a bed or pen by means of the ties 21 to 24 and 39.

In this position, the child is secured in the cover 10, and should he try to crawl headwise from under the cover, the tie member 40, which is secured between the crotch of the body unit and the under side of the sheet 11, will serve to restrain him. However, it will be observed that the child has considerable freedom of movement, and when he turns over, the upper part of the tie member will turn with him, and there is no danger of his becoming entangled with any of the bed equipment. With this construction, the tie member extending from and attached to the crotch of the body garment, is substantially in alignment with the natural body axis of the child. Thus, when the child turns over in his bed, the only effect is to twist slightly the tie member 40, and the child's arms, head and legs are not interfered with. It will be seen that the point of attachment of the securing means (at the crotch of the body unit) is on the longitudinal axis of the child's body and may turn with the child without wrapping about the child's body.

The plait construction in the cover 10 serves to give the child freedom and comfort. With the ties 21 to 24 and 39 drawn tight to the bed frame, the side seams 15, 16 and 17 will be drawn taut and will lie even with the surface of the mattress or other surface on which the child lays. However, the plaits 18 and 19 will expand to permit the extra fullness about the child's body. At the same time, the appearance of the cover will remain neat and without undue wrinkles.

When it is necessary to change a baby's diapers, the improved structure will permit easy access, and the attendant may either change the baby in his bed or remove him to another place to do this. If the baby is to be changed at the bed, the attendant may simply release the fastening at the buttons 35 and turn up the back body

portion 29. This does not disturb the fastening of the tie member 40 either to the body garment 27 or to the sheet 11. On the other hand, if it is desired to change the baby at another place, the attachment of the tie member 40 to the sheet 11 may be released as by unbuttoning the buttons 38 from the loops 24, which leaves the child free to be lifted from the bed.

Figure 5 shows a modified form of body structure and tie member which has certain advantages. As will be seen from the drawing, this simple structure has the arm openings 50 and 51, the neck opening 52, and has the back side 53 extending down and attached to the front side 54 by the buttons 55 to thus form a crotch portion. Each of the front and back portions 54 and 53 has extensions which protrude downwardly from the crotch of the body unit to form a tie member 60 comprising the front extension strip 61 and the co-extensive back extension strip 62. The extension strip 61 is provided at its lower end with the buttons 63 which are adapted to extend through the buttonholes 64 in the end portion of the extension strip 62, and to engage one of the loop series 24, 25 or 26, in the same way as the buttons 38 of the embodiment illustrated in Fig. 3.

In the use of the body garment illustrated in Fig. 5 in connection with the improved cover device, the attendant may unfasten the buttons 63 from the buttonholes 64 and may unfasten the buttons 66 from the buttonholes 67. This frees the attachment at the crotch portion and allows the strips 61 and 62 to be thrown back to open the lower end of the garment. The garment, open in this way, may be slipped down over the child's head so that the child's head passes into the neck opening 52 and his arms into the openings 50 and 51. The buttons 66 may then be fastened to provide the crotch, and the child's legs will extend through the openings 68 and 69. The buttons 63 may then be passed through the buttonholes 64 and fastened to the loops 24, 25 or 26 as described in connection with the embodiment of Fig. 3.

The foregoing detailed description has been given for clearness of understanding only and is not intended in a limiting sense. It is understood that many modifications may be constructed and many changes made without departing from the spirit of the invention.

This application is a continuation-in-part of my application Serial No. 442,567, filed May 11, 1942, now Patent No. 2,401,026, dated May 28, 1946, and entitled Infant's sleeping garment combination.

I claim:

1. In an infant's sleeping garment structure of the character set forth, a sheet, means for securing the corner portions of the sheet to a bed, a body garment extending about the body of the child and provided with openings through which the legs of the child extend, said body garment having a crotch portion received between the legs of the child and a tie member narrower than said body garment and equal to about half its length, and means for securing the tie member to said sheet at an intermediate point thereon and in line with the longitudinal axis of the child's body.

2. In an infant's sleeping garment structure of the character set forth, a sheet, means for securing the corner portions of the sheet to a bed, a body garment extending about the body of the child and provided with openings through which the legs of the child extend, said body garment having a crotch portion received between the legs of the child, a tie member equal in length to about half the length of the garment and being of a width narrower than said garment and lying between the legs of the child, and means securing the lower end of said tie member to said sheet at a central portion thereof and in line with the longitudinal axis of the child's body within said garment.

LIBERA L. STEIGERWALD.
